(57) **CLAIM**

The ornamental design for a combined radio receiver and clock, as shown and described.

DESCRIPTION

FIG. 1 is a perspective view of an embodiment of a combined radio receiver and clock showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of another embodiment of a combined radio receiver and clock showing my new design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

Portions of FIGS. 1-14 that are shown as broken lines are for illustrative purpose only and form no part of the claimed design. The dot-dash broken lines shown in FIGS. 1, 2, and 6, define but are not included in, the boundaries of the claimed design.
